UNITED STATES PATENT OFFICE

2,442,744

BUFFING OR POLISHING MACHINE

Carl J. Geiger, New York, N. Y.

Application March 19, 1947, Serial No. 735,713

1 Claim. (Cl. 51—166)

1

This invention relates to buffing, polishing or grinding machines whose principal object is to provide a structure that will be compact so that it can be accommodated in a relatively small space and be convenient for home use.

Another object is to provide a structure that will be simple, of a relatively light weight and cheap to manufacture.

Still another object is to arrange the buffing wheels and the motor driving the same so that the centrifugal forces thereof will counter-balance one another.

And still another object is to mount all operating parts so as to reduce vibrations to a minimum.

Another object is to provide automatic means for the removal and collection of the dust directly from the region around the buffing wheels.

With these and other objects in view that will be apparent from the detailed description of my invention the latter substantially consists in the novel construction, combination and arrangement of parts as will be hereinafter fully described and defined in the appended claim.

In the accompanying drawing which constitutes part of this specification and in which similar reference numerals denote corresponding parts;

Fig. 1 is a perspective view of my new buffing machine;

Fig. 2 is an end view thereof;

Fig. 3 is a top plan view thereof, and

Fig. 4 is a rear view thereof.

Referring more in detail to the drawing, my machine comprises a base 10, an upright wall 11 fixed on said base, a platform 12 projecting from one side of said wall and a buffing wheel support 13 projecting from the opposite side of said wall. To reduce the weight of the machine, the wall, platform and support may be constructed from seamless pipes 14 covered by steel or aluminum plates 15, 16 and 17, suitably welded together.

Suitably fixed to the front end of the support 13 are bearings 18 (only one being shown) for a horizontal shaft 19 on which are fixed the buffing or polishing wheels 20. The support 13 is advantageously made in form of a hood to enclose the means for transmitting motion to the shaft 19, as belt or gears, from the motor 21, mounted on the opposite side of the wall 11. Suitably supported on the base 10 below the platform 12 is a dust collecting chamber 24 in which is mounted a suitable rotary blower, whose shaft 25¹ may be driven from the motor 21 through

2

pulleys and belt 25, 26, respectively, or in any other suitable manner.

Suitably fixed to the support 13 to envelop the upper parts of the wheels 20 are semi-cylindrical shields 28. Attached to these shields and opening into the spaces directly around the wheels are conduits 27 which extend through the wall 11 and platform 12 and terminate in the dust collecting chamber 24.

10 The construction of the machine is such that the parts on one side of the upright wall are adapted to counterbalance those on the opposite side, so that in operation vibration will be considerably reduced.

15 What I claim is:

As an article of manufacture, a buffing machine or the like, comprising a base plate, an upright plate wall mounted thereon, a horizontal platform projecting from the rear face of said wall, a motor mounted on said platform, adjacent to the rear face of said wall, a housing projecting centrally and forwardly from the upper part of the front face of said wall, a horizontal shaft extending parallel to said wall in the plane of the axis of said motor, and borne in the forward end of said housing, buffing wheels fixed on said shaft, one on each side of said housing, a motion transmitting means for said shaft from said motor, concealed within said housing, a dust collecting chamber mounted on said base plate at the rear of said wall below said platform, rotary means for creating suction in said chamber, means for transmitting motion to said suction creating means from said motor, shields mounted above said buffing wheels and conduits connected to and leading from within said shields through said wall into the dust collecting chamber.

CARL J. GEIGER.
